COLLARS FOR SHIRTS AND LIKE GARMENTS

Lajos Bihaly, London, England, assignor to Trubenised Company (Registered Trust), Vaduz, Liechtenstein

Application December 29, 1953, Serial No. 400,975

Claims priority, application Great Britain
January 15, 1953

5 Claims. (Cl. 2—131)

In so called one-piece collars for shirts and like garments the outer part, or top, of the collar is cut integral with the inner part, or band, and (as at present made) such collars will lie completely flat before folding about the curved line which separates the collar top and the band.

We have found that while satisfactory collars can be cut in this way when the material of the collar is stiffened (either by fusing together the several plies of fabric composing the collar, or by other means), soft collars cut in a similar manner are unsatisfactory in wear, the collar top tending to crowd round to the front of the collar, giving a "bandage" effect.

In conventional soft collars, in which the collar top and band are cut separately and joined together by stitching the collar top is curved, but the band is cut as a strip which is either completely straight, or is curved very much less sharply than the collar top. In making up the collar, the substantially straight upper edge of the band is joined by the collar banding seam to the concave upper edge of the collar top, so that the completed collar will not lie flat. The "spring" thus imparted to the collar top by the difference in curvature between the two parts of the collar plays an important part in determining the proper set of the collar in wear.

In accordance with the present invention a one-piece soft collar is so constructed that the collar top is given a spring similar to that obtained in conventionally made collars, thereby greatly improving the appearance and comfort of the collar in wear.

The invention comprises a method of making a one-piece soft collar in which three pieces of fabric, for constituting respectively the face ply, the lining and the backing ply of the collar (each piece comprising a band portion in the form of a curved strip and a top portion integrally joined to the band portion along the upper or outer edge of the latter), are superimposed in register and secured together around their peripheries, characterised in that the lining ply is formed with slits extending from the lower or inner edge of its band portion across at least part of the width of the band and that during the securing together of the plies along the lower edge of the band, longitudinal tension is applied to the band while the upper edge of the band is held against extension, so that the band is straightened more or less completely (the band portions of the face and lining plies being thereby distorted and the slits in the lining opened out), the securing together of the plies along the lower edge of the band serving to retain the band in partly straightened condition.

The collar is conveniently made by the well known run and turn method, manufacture being carried out in the conventional manner (except that the lining ply used has the free longitudinal edge of its band portion divided into a number of separate sections) until the closing operation, during which tension is applied to the band. The invention thus comprises also a method of making

2

a one-piece soft collar in which two similarly shaped, unitary pieces of fabric for constituting respectively the face ply and the backing ply of the collar, each piece comprising a band portion and a top portion integrally united therewith, and a third unitary piece of fabric for constituting the lining of the collar, which is shaped similarly to the first two pieces but is divided along the free longitudinal edge of its band portion into a plurality of separate sections, are superimposed in register with one another, the lining constituting one of the outer plies of the assembly, the assembled plies are secured together by stitching around a major part of their periphery, leaving open the free edge of the band portion, the lining ply is secured (either before or after effecting such stitching) against longitudinal extension along the line of junction of the band and top portions thereof, the stitched assembly is turned inside out so as to bring the lining ply between the first two plies, tension is applied between the ends of the band portion of the assembly so as to extend the free longitudinal edge thereof, and while so tensioned the plies are stitched or otherwise fastened together along the free edge of the band portion. The invention also comprises collars having the structure produced by the above methods, so that the invention includes a one-piece soft collar comprising three superimposed pieces of fabric each comprising a top portion and a band portion integrally united with one another along the fold line of the collar, the superimposed pieces being secured together around their peripheries, characterised in that the band portion of the collar is permanently distorted so that it will not lie flat in the same plane as the top portion, the band portion of the central ply being divided into a plurality of separate sections which are held spaced apart from one another by their attachment to the two outer plies of fabric.

The accompanying drawing illustrates by way of preferred example a particular manner of carrying the invention into effect. In this drawing Figure 1 is a plan view of the collar assembly (with parts broken away to show the internal structure) after the running stitch has been made but before the collar is turned; while Figure 2 is a similar view of the assembly after it has been turned and the closing stitch made.

Referring to the drawing, the three similarly shaped and sized, unitary pieces of fabric (face ply 1, lining 2 and backing ply 3) from which the collar is to be formed are cut to the same shape as in the known one-piece collars, each comprising a curved collar top portion A and a curved band portion B which are integrally united with one another along the curved line 4 about which the collar is eventually to be folded. The band portion B of the lining ply is cut through along a plurality of transverse lines, the slits 5 thus produced extending outwardly from the lower edge of the blank across the major part of the width of the band portion. The plies are assembled in register with one another with the lining uppermost and are secured together along a major portion of their periphery by a running stitch 6, this line of stitching extending completely around the periphery of the assembly except along the free longitudinal edge of the band portion, namely the edge opposite to that along which it is united to the top portion A of the collar. Either before or after the running operation, a narrow tape 7, which serves to determine the fold line, is adhesively secured to the band portion of the lining ply, the outer edge of the tape running along the desired fold line 4. Figure 1 shows the assembly after completion of the foregoing operations. The collar is then turned, and at this stage the collar will still lie completely flat and is similar in shape to known one-piece collars. Before the final closing stitch is made, tension is applied

to the ends of the curved band portion B, so that this portion is distorted into the form of a substantially straight strip. The slits 5 in the lining ply are thereby opened up to form wedge shaped slots 15 (Figure 2) while the relatively soft material of the face and backing plies readily yields to deformation. The closing stitch 8 is made while the band is in this stretched condition and the substantially straight form of the band portion is thus permanently fixed. Figure 2 shows the assembly after the closing stitch has been made and with the distorted band portion B lying in a flat plane, the portion A being accordingly distorted into a non-planar form. It will be appreciated that it is still possible for the top portion A to be laid flat, but the band portion B will not then lie flat in the same plane. For the sake of clarity, the degree of distortion is somewhat exaggerated in the drawing.

The attachment of the tape 7 to the lining 2 serves to secure the lining ply against longitudinal extension along the line of junction of the band and top portions of the lining ply when the band is placed under tension. The distortion produced by the tensioning operation is thus confined to the band side of the desired fold line and the top portion A of the collar remains undistorted. The tape also serves to provide a discontinuity in the stiffness of the collar assembly across the width thereof, thereby increasing the tendency of the collar to fold along the desired line 4.

While the use of such a fold-line-determining tape is preferred, other means may be employed for separating the band portion from the top portion and confining to the band portion the distortion produced by the stretching during the final operation. Thus, extension of the lining ply along the line of junction between the band and top portions thereof, that is along the desired fold line 4, may be prevented, or reduced to an acceptably low value, by means of a row of stitches applied along that line. These stitches may pass through the lining ply only, or they may secure the lining to one of the other plies, or to both of the other plies. In the first two cases the stitches along the fold line may conveniently be applied before the running and turning operations, but in the last case they must obviously be applied only after the plies have been brought into their final relative positions.

I claim:

1. In a method of making a one-piece soft collar by superimposing in register with one another three pieces of fabric, for constituting respectively the face ply, the lining and the backing ply of the collar, each piece comprising a band portion in the form of a curved strip and a top portion integrally joined to the band portion along the outer edge of the latter, and securing the superimposed plies together around their peripheries, the steps of forming the lining ply with slits extending from the lower edge of its band portion across at least part of the width of the band, and of applying longitudinal tension to the band while holding the upper edge of the band against extension, so that the band is straightened, the band portions of the face and lining plies being thereby distorted and the slits in the lining opened out, during the operation of securing the plies together along the lower edge of the band, the said securing operation serving to retain the band in partly straightened condition.

2. In a method of making a one-piece soft collar by superimposing in register with one another three pieces of fabric, for constituting respectively the face ply, the lining and the backing ply of the collar, each piece comprising a band portion in the form of a curved strip and a top portion integrally joined to the band portion along the outer edge of the latter, the lining constituting one of the outer plies of the assembly, securing the assembled plies together by a running stitch extending around a

major part of their periphery but leaving open the free edge of the band portion, turning the stitched assembly inside out so as to bring the lining ply between the first two plies, and securing the plies together by a closing stitch extending along the free edge of the band portion, the steps of dividing the lining along the free longitudinal edge of its band portion into a plurality of separate sections prior to making said closing stitch, securing the lining ply against longitudinal extension along the line of junction of its band and top portions prior to making said closing stitch, and applying tension between the ends of the band portion of the assembly, so as to extend the free longitudinal edge thereof, during the making of said closing stitch.

15 3. In a method of making a one-piece soft collar by superimposing in register with one another three pieces of fabric, for constituting respectively the face ply, the lining and the backing ply of the collar, each piece comprising a band portion in the form of a curved strip and a top portion integrally joined to the band portion along the outer edge of the latter, the lining constituting one of the outer plies of the assembly, securing the assembled plies together by a running stitch extending around a major part of their periphery but leaving open the free edge of the band portion, turning the stitched assembly inside out so as to bring the lining ply between the first two plies, and securing the plies together by a closing stitch extending along the free edge of the band portion, the steps of dividing the band portion of the lining transversely into a plurality of sections separate from one another at the free edge of the band but integrally united with one another at the line of junction between the band and top portions of the lining prior to making said closing stitch, adhesively securing to the band portion of the lining a narrow tape with one edge of said tape extending along said line of junction prior to making said closing stitch, applying tension to the band portion of the three-ply assembly after turning the assembly inside out but before making said closing stitch so as to move the sections of the band portion of the lining away from one another and distort the band portions of the face and backing plies, and maintaining said tension while making said closing stitch, whereby to secure said sections in separated relationship to said face and backing plies.

30 4. A one-piece soft collar comprising three superimposed pieces of fabric, each comprising a top portion and a band portion integrally united with one another along the fold line of the collar, the superimposed pieces being secured together around their peripheries, but being free from one another over the major portion of their areas, characterized in that the band portion of the collar is permanently distorted relative to the collar top by elongation along the edge remote from the top portion, so that it will not lie flat in the same plane as the top portion, the band portion of the central ply being divided by V-shaped cut-outs into a plurality of separate sections which are held by their attachment to the two outer plies of fabric spaced further apart from one another than they would lie if the central ply were undivided.

35 5. A one-piece soft collar comprising three superimposed similarly shaped pieces of fabric, each comprising a top portion and a band portion integrally united with one another along the fold line of the collar, means for securing the superimposed plies together around their peripheries, but leaving them free from one another over the major portion of their area, the band portion of the two outermost plies being continuous while the band portion of the central ply is transversely divided into sections by V-shaped cut-outs, the edges of said sections furthest from the top portion being attached to the two outermost plies by said peripheral securing means at

positions further apart from one another than they were in the undivided fabric, whereby the band portion of the central ply is held with its edge remote from the top portion in elongated condition and means extending along the line of junction of the band and top portions of the central ply for holding the central ply against stretching along said line of junction.
